PIANO KEY MOUNTING

Filed Feb. 28, 1927

UNITED STATES PATENT OFFICE.

WALTER A. GOBLE, OF GRAND RAPIDS, MICHIGAN.

PIANO-KEY MOUNTING.

Application filed February 28, 1927. Serial No. 171,536.

This invention relates to a piano key mounting by means of which it is readily possible to individually remove any key very quickly and easily without disturbing the rest of the structure of the piano in any manner. This is of particular value in connection with player pianos wherein it is now impossible to remove the conventional style keys in most makes, at least, without first removing the player stack, for the reason that such stack is so close to the keys that the keys cannot be lifted high enough to clear the conventional and usual style of key pin at the point where mounted on the balance rail.

A further object and purpose of this invention is to provide a novel method of mounting the keys so that not only may they be thus readily removed as previously stated, but also that same may be adjusted to bring all of the keys to the same level; and this adjustment is one which can be performed almost instantly with respect to any particular key, requiring no laborious building up and tearing down with additions and removals of paper washers of varying thicknesses such as are now required to level the keys.

A still further object is to secure the above results without detriment to the strength of the keys at the balance rail point and without cutting away portions of the key when mounting the same on the balance rail with a consequent weakening thereof, as is now almost universal practice.

In addition to the novel and useful way of pivoting and adjusting the keys on the balance rail, another object of the invention is to provide very simple and readily regulated means for maintaining the keys in proper position to keep them from tipping laterally in either direction. These improvements which I have made are exceptionally simple, practical and economical to make, their use resulting in considerable saving of time for the manufacturer, while the repairing and adjusting the keys is greatly simplified.

For an understanding of the invention whereby these ends are attained, reference may be had to the following description taken in connection with the accompanying drawings, in which,

Fig. 1 is a fragmentary plan view illustrating the manner of pivotally mounting

the keys, and one way in which the same may be held against lateral tipping in either direction.

Fig. 2 is a side elevation and vertical section showing the manner in which the keys are mounted on the balance rail.

Figs. 3 and 4 are fragmentary plan views of the intermediate portions of keys where the same are pivotally mounted and held from laterally tipping.

Fig. 5 is a vertical transverse section through one of the keys, the balance rail being shown fragmentarily in longitudinal section, illustrating the construction shown in Figures 2 and 3 for pivotally mounting the keys and holding the same for lateral tipping.

Fig. 6 is a fragmentary enlarged longitudinal section through the intermediate portion of a key and a transverse section through the balance rail on which it is mounted, and

Fig. 7 is a view similar to that shown in Figure 5, but illustrating a different specific form of construction for holding each key from lateral tipping.

Like reference characters refer to like parts in the different figures of the drawings.

In the construction shown, a frame 1 is provided above which the keys are mounted. At the front edge of the frame 1 a front rail 2 is secured transversely thereof from which vertical key pins 3 extend into suitable openings in the under side of the keys, and a punching 4 of felt or like material is located around each pin at the upper side of the rail 2 against which the under sides of the front ends of the keys strike when the same are depressed in playing.

A distance back of the rail 2, a balance rail 5 of wood or equivalent material is secured transversely of the frame 1 parallel to the front rail 2 in which at its upper side a number of small openings 6 are made, one for each key, the purpose of which will later appear. At the rear of the frame 1, a third or back rail 7 is secured transversely of the bed on the upper side of which is a felt strip 8, the rear ends of the keys normally bearing against the felt 8. The keys are of wood, and with my invention, the front end portions 9 thereof are substantially square in cross section at their upper sides equipped with the usual facing 10, which

may be ivory for the white keys and stained or painted wood or ebony for the black keys, said black keys being shown at 10^a.

The rear portions of the keys are slightly 5 narrowed as indicated at 11 by removing some of the material at each vertical side so that when a plurality of keys are mounted side by side, there are spaces 12 between the keys back of the wider front portions 9 10 thereof.

Through each key a screw 13 is passed, the screw being threaded substantially for its entire length and at its lower end below the thread having a tapered point 14. On 15 this tapered point a washer 15 of metal or other suitable material is driven underneath which a pad 16, which may be of felt, is placed to bear against the upper side of the balance rail 5, the tapered end 14 of the 20 screw entering an opening 6, to which reference has previously been made.

The keys are thus pivotally mounted between their ends on the balance rail. Any key can be very easily removed by merely 25 lifting the front end until it is disengaged from its key pin 3, this at the same time lifting its pivot screw 13 at its lower end from the opening 6 in which it is located, whereupon the key may be drawn in the 30 direction of its length outwardly at the front. It is also evident that the adjustment of the key may be very quickly and expeditiously done. By merely applying a screw driver to the head of a screw 13, any key 35 may be raised or lowered and all of the keys may be adjusted to the same plane at their front upper sides by bringing them against the under side of a straight edge as is evident. This adjustment of the dip of 40 the keys is of great value in the manufacture of pianos. The present practice is to build the key up above the balance rail to the desired level by using punching of cardboard or paper, which must be carefully 45 selected as to thickness and by repeated trial applied to the keys until all of the keys are located at a desired level, this necessitating a removal of the keys many times with trying operations before a final perfect adjustment is secured; while with my invention 50 the adjustment of any key is effected almost instantly.

By reason of the removal of portions of the material of each key at the sides thereof 55 at the back, the rear end portions of the keys will not rub against each other should any of the keys warp and bend laterally as frequently it occurs.

The spaces, indicated at 12, are wide 60 enough to take care of any such bending and warping, while such spaces are also of utility to furnish space for mounting a prop pin 17 between keys and on the balance rail to hold the key against any lateral tipping. 65 One of the forms which I may use is shown

in Figs. 3 to 6 inclusive. The prop pin 17 made of metal or any other suitable material is driven into or otherwise attached to the balance rail 5, so as to extend vertically one at one side of each key. Between the prop pin and the side of the key, a felt pad 18 may be placed and cemented to the side of the key as shown. As screw 19 having an end portion 20 turned at right angles is screwed into the same side of the key a short 75 distance from the prop pin 17, so that said part 20 lies parallel to the side of the key and its inner side carries a facing 21 of felt, the prop pin 17 passes between the two felt facings 18 and 21, as fully shown in Figs. 80 3 and 4. This serves to maintain the key in proper position. The prop pin 17 may be of oval form so that by turning the same about its vertical axis adjustment may be readily made for any wear which takes 85 place. Of course the pin could be circular in cross section in which case adjustment is readily made by bending the part 20 towards or away from the pin as may be necessary. 90

Another form of prop pin is shown in Fig. 7. The pin 22 extends vertically at one side of the key bearing against the felt 18, and at a distance above the upper side of the key is turned horizontally across the key as indicated in 23, and then turned downwardly at right angles, as shown at 24, so that its lower portion lies below the upper side of the key. A felt pad 25 is attached to this side of the key directly opposite the pad 18, 100 so as to bear against the lower end of part 24 of the prop pin, constructed as shown in Fig. 7. This also maintains the keys in proper position and keeps them from tipping sidewise, wear in such case being taken care 105 of by bending the free end portion 24 towards the key as may be needed.

This construction of piano key mounting while simple in form, is particularly useful both from a manufacturing and a service 110 standpoint. The keys are not weakened when mounted on the balance rail as is now the present practice wherein parts of the keys are cut away to permit the use of the conventional style balance rail pins and 115 wooden key buttons. Removal of the key with this invention is particularly simple and easy as has been fully described. Adjustment of the key for "dip" is likewise simple and easy, requiring little or no skill. 120 The narrowing of the keys at their rear portions keeps them from rubbing together should any warp of the key occur, so that they do not have to be removed and planed off, in order that they may work freely. The 125 device used for preventing any sidewise tipping of the keys is economical to make and easily applied and does not interfere in any manner with the mounting, adjustment, and removal of the key when it is necessary in 130

tuning or repairing of the piano. All of these features combine to make the invention of great practical value.

The invention is defined in the appended 5 claims and is to be considered comprehensive of all forms of construction coming within their scope.

I claim:

1. In a construction of the class described, 10 a balance rail having openings in its upper side, a plurality of piano keys located above and across said rail, a balance pin projected from the lower side of each key having its lower end seated in an opening in said rail, 15 said keys at their rear portions having portions at their vertical sides cut away whereby spaces are made between the keys, and prop means attached to the balance rail and located in said spaces for holding the keys 20 from side tipping.
2. In a construction of the class described, 25 a balance rail having openings in its upper side, a plurality of piano keys located above and across said rail, a screw having a reduced lower end threaded downwardly through each key and having said lower end seated in an opening in said rail, a washer located over the reduced end of the screw, a pad under said washer bearing against the balance 30 rail, and means located between the keys and attached to the balance rail for holding the keys from sideways tipping.
3. In a construction of the class described, 35 a balance rail, a plurality of piano keys located above and across the balance rail, means for pivotally mounting the keys on said rail, said means being vertically adjustable through the keys to raise or lower the outer ends thereof, and means attached to 40 the balance rail and located between the keys for holding each key from sideways tipping in either direction.
4. In a construction of the class described, 45 a balance rail, a plurality of piano keys located above and across the rail, each of the keys having portions at the vertical sides thereof removed back of the front ends

thereof, means for pivotally mounting the keys on said rail, said means being vertically adjustable through the keys to raise or lower 50 the outer ends thereof, and a prop pin attached to the balance rail and extending vertically alongside each key to hold the same from sideways tipping.

5. In a construction of the class described, 55 a balance rail, a plurality of piano keys located above and across the rail, each of said keys having portions at the vertical sides thereof removed back of the front ends thereof, means for pivotally mounting the 60 keys on said rail, said means being vertically adjustable through the keys to raise or lower the outer ends thereof, a prop pin attached to the balance rail and extending vertically 65 alongside each key in the spaces made between the keys through said removal of side portions thereof, and means associated with each of said prop pins, said pins holding the keys from lateral tipping in one direction and said last mentioned means holding the 70 keys from lateral tipping in the other direction.

6. In a construction of the class described, 75 a balance rail having openings in its upper side, a plurality of piano keys located above and across said rail, means for pivotally and detachably mounting the keys on said rail and a prop pin attached to the balance rail and extending vertically alongside each key 80 between the keys to hold the same from sideways tipping.

7. In a construction of the class described, 85 a balance rail, a plurality of piano keys located above and across the rail, means for pivotally and removably mounting the keys on said rail, a prop pin attached to the balance rail and extending vertically alongside each key between the keys and means on each key associated with a respective prop pin to hold the keys from sideways tipping. 90

In testimony whereof I affix my signature.

WALTER A. GOBLE.
